Inventor:
Ernest Trova,
By Ripley Kingsland
His Attorney.

UNITED STATES PATENT OFFICE.

ERNEST TROVA, OF ST. LOUIS, MISSOURI.

HOVER.

Application filed February 15, 1923. Serial No. 619,175.

To all whom it may concern:

Be it known that I, ERNEST TROVA, a citizen of the United States, residing at the city of St. Louis and State of Missouri, have 5 invented a new and useful Hover, of which the following is a specification.

This invention relates to electrically heated hovers, and consists in the novel construction hereinafter disclosed.

10 An object of the invention is to provide an electrically heated hover designed to maintain a substantially uniform heat and to be under automatic control of the temperature within the hover.

15 Another object of the invention is to provide a heating element design for a hover, together with automatic means for controlling the operation of the heating element, said controlling means being under the influence of heat within the hover.

20 Another object of the invention is to provide a hover including a hover chamber, a heat radiating drum, a heating element removably supported within the drum, and 25 automatic means for controlling the heating element, the condition of said automatic means being visibly indicated by a visible signal.

Additional advantages of the construction 30 will be apparent from the following detailed description thereof taken in connection with the accompanying drawings, in which—

Fig. 1 is a plan view.

Fig. 2 is a vertical section.

35 Fig. 3 is a front elevation of the automatic controlling means for the heater element, with the dial and indicating hand of the indicator removed.

Fig. 4 is a rear elevation of the same.

40 Fig. 5 is a vertical section on the line 5—5 of Fig. 3.

In the embodiment of the invention illustrated in the drawing the hover is shown as comprising a heat radiating chamber including a cylindrical portion 1, upwardly inclined walls 2 and a drum 3, the drum 3 including spaced walls with an intermediate layer of insulating material 4. At the side edges of the drum and supported on a ring 5 is a curtain 6 forming an enclosed space between the bottom of the heat radiating chamber and the curtain. At the center of the drum is an opening for the insertion of the heating element, which opening is closed by the support for the heating element and the associated parts.

The support for the heating element comprises a metallic ring 7 having a flange 8 for insertion in the opening in the drum. A handle 9 is provided for the support so that the heating element may be readily raised out of its position and inserted. Supported by the ring 8 is a disc 10 of insulating material. Depending from the under face of the disc 10 are straps 11 supporting a cylinder 12 of insulating material upon which a resistance coil 13 is wound.

The straps 11 constitute the terminal elements of the resistance coil and have connected to their upper ends the leads 14 of a light socket 15 in which is mounted a light bulb 16. The leads 17 are connected with an automatic heat controlling switch the detailed structure of which is the subject matter of my co-pending application filed July 17, 1922, Serial No. 575,454. It is sufficient for the purpose of the present application to say that the switch includes a casing 18 supported on the top face of the disc 10. A heat responsive element 19 is connected with and extends into the casing at one end and downwardly into the heat radiating chamber at the other end having an angular branch 20 located at a slight distance above the bottom wall of the heat radiating chamber. The standard of the heat responsive tube is encased in a cylinder 21 of heat insulating material so that the zone of heat adjacent to the branch 20 controls the operation of the tube. The heat responsive element is of the Bourdon tube type and has its upper end connected by a link 22 with a slotted arm 23. The arm 23 is pivoted for rocking movement and carries at its outer end a rack 24 which engages a pinion 25 on a shaft 26, said shaft 26 carrying the indicating hand 27 at its outer end.

The switch elements are connected on an insulated block 28, said block being supported on a plate 29. A spring plate contact member 30 has one of the leads connected thereto and a contact plate 31 has the other lead connected thereto. The plate 31 is free at its outer end and is engaged by a pin 32 connected near the end of the heat responsive element. The plate 29 is raised and lowered by means of a set screw 33, so that it may be adjusted in a way that the contact between the ends of the plates 30 and 31 respectively is broken by a greater or less degree of movement of the end of the heat responsive element. It will be under-

stood that the light is in the same circuit so that when the circuit is closed the light will indicate visually that condition of the circuit.

5 While the form of heat controlling element illustrated and described is preferable, it will be understood that other forms of heat controlling elements may be used if desired.

10 In order to protect the depending structure supported by the plate 10 a cylindrical cage 34 is provided.

I am aware that the invention may be modified in certain particulars without departing from the spirit and scope of the invention. I do not restrict myself unessentially, but what I claim and desire to secure by Letters Patent is:—

15 1. A hover comprising a chamber composed of an upright wall, a wall united with and flaring upwardly and outwardly from the upper end of said upright wall, and a top wall connected with the outer edge of said flaring wall; an electric heater supported within said chamber in the plane of the space between said flaring and top walls, and means extending below said heater and responsive to the heat below the heater and near the bottom of the hover to control the heater.

20 2. A hover comprising a chamber composed of an upright wall, a wall united with

and flaring upwardly and outwardly from the upper end of said upright wall, and a top wall connected with the outer edge of said flaring wall; an electric heater supported within said chamber in the plane of the space between said flaring and top walls; an electric circuit for supplying energy to said heater; mechanism supported above the top wall for opening and closing said circuit; and a heat responsive device extending from said mechanism into said chamber to a plane near the bottom of the hover and below said heater to open said circuit. 45

25 3. A device of the character described, comprising a heat radiating chamber composed of an upright wall portion and a wall portion flaring upwardly and outwardly from said upright portion, said chamber 50 having an opening in the top thereof, an insulating support mounted in said opening, a heating element suspended from said support and being on a plane substantially at the juncture of the walls of said heating chamber, and a heat responsive element for controlling the circuit of said heating element, said heat responsive element having a member extending downwardly in the heat radiating chamber, and an insulating tube 55 for said member leaving exposed the lower end thereof so that it is responsive to the heat in the lower strata of said chamber. 60

ERNEST TROVA.
